UNITED STATES PATENT OFFICE.

ANDERS ANDERSEN PINDSTOFTE, OF COPENHAGEN, DENMARK.

PRESSURE-REGULATOR.

1,383,481.

Specification of Letters Patent.

Patented July 5, 1921.

Application filed August 28, 1919. Serial No. 320,525.

To all whom it may concern:

Be it known that I, ANDERS ANDERSEN PINDSTOFTE, manufacturer of engines, a subject of the Kingdom of Denmark, residing 5 at No. 62 Frederiksberg Allé, in the city of Copenhagen, Denmark, have invented certain new and useful Improvements in Pressure-Regulators, of which the following is a specification.

10 The present invention relates to a pressure regulator suitable for gases as well as for liquids, the invention being mainly characterized in that the diaphragm is not in firm connection with those parts in the pressure regulator which are actuated by or articulate the diaphragm, while the valve is operating. The invention is further characterized in that the guiding parts located above and below the inlet opening, respectively, 15 20 in the valve are not in firm connection with each other.

On the drawing there is illustrated one manner of constructing the invention.

Figures 1 and 2 show two vertical sections 25 of the pressure regulator, at right angles to each other.

Fig. 3 shows the same in top view, and

Fig. 4 a horizontal section along the line A—B in Fig. 2.

30 In the construction shown, the valve chamber 1 is limited by a cylindrical wall 2 held tightly between a cover 3 and a bottom part 4. A tube 5 extends through the cylinder wall 2, and is fitted with a downwardly 35 directed inlet opening 6. The highly compressed gas or liquid, whose pressure is to be reduced by the regulator, flows now into the valve chamber 1. Immediately below the inlet opening 6, there is provided a valve 40 seat 7 or the like, inserted in the top face of the plunger member 8, which is disposed below the inlet opening and consists of a guiding head or disk 10 and a downwardly directed stem 9. The lower portion of the 45 stem 9 is reduced in diameter, and is encircled by a helical spring 11 tending to press the valve seat 7 against the inlet opening 6. The closing pressure of the spring may 50 be varied by screwing up or down, relatively to the bottom plate 4, the ring 12 which guides the stem. The ring 12, as well as the head 10, are fitted with the necessary holes for the passage of the air or liquid through the regulator.

55 The head 10 supports for instance three studs 13, or the like, which are adjustable

relatively to the head and are located rather far from the valve seat 7, the upper ends of the said studs resting against a guiding disk 14, which rests loosely above the inlet tube 5, 60 its edge being guided against the cylinder wall 2. The device may also be constructed in the manner indicated in Fig. 2, where the studs 13 are screwed into the guiding disk 14, their lower ends resting against the 65 guiding flange 10. Between the guiding disk 14 and the diaphragm 15, there is provided another loose guiding disk 16, which is also guided against the cylinder wall, and is fitted with a centrally disposed and down- 70 wardly directed pin or screw 17, rounded at its lower end and resting on the disk 14. The outer portion of the top face of the disk 16 is thinned, so that there is thereby produced an open annular space along the outer 75 portion of the diaphragm.

The diaphragm 15 is disposed on top of the disk 16, and is held tightly between the cylinder wall 2 and the top portion 3 of the pressure regulator. Above the diaphragm 80 there is provided a loading plunger comprising a head or disk 19 and a stem 18. The head 19, as well as the stem 18, are guided in the top part of the regulator. The upper rounded end of the stem 18 supports a disk 85 20 receiving the pressure of the loading spring 21. The pressure of the spring may be varied by the screw 22 being screwed more or less down.

By constructing the pressure regulator as 90 here described, the great advantage is attained that the diaphragm lies loose between the loading plunger 19 and the guiding disk 16, so that the diaphragm will be far less strained than a corresponding diaphragm 95 fastened to a continuous spindle, and so that the friction is reduced to a minimum owing to the devices above and below the inlet opening and to the loose disks. By means of the studs 13, there is further provided 100 free escape in all directions for the high-pressure fluid or gas supplied.

I claim as my invention—

105 In a pressure regulator, the combination of a spring-loaded plunger; a casing wherein the plunger is guided; a disk loosely mounted in the casing; a diaphragm mounted in said casing between said plunger and disk and free of positive connection with both of them, the upper surface of the diaphragm 110 loosely contacting with the head of the plunger; a second disk loosely mounted in said

casing beneath the first-named disk, one of said disks having a central vertical bearing member with which the other disk is engaged; a second spring-loaded plunger guided in the casing below the second disk and having its head spaced from the same and provided with a valve seat; the head of the second plunger and the second disk constituting companion parts, one of which is

provided with adjustable, vertically-projecting members engaging the other part to regulate the distance between the two parts; and an inlet tube for the fluid to be regulated having an open end coöperative with the valve seat. 10

15 In testimony whereof I have affixed my signature.

ANDERS ANDERSEN PINDSTOFTE.
